INVENTOR
Samuel Lipsius
ATTORNEY

UNITED STATES PATENT OFFICE.

SAMUEL LIPSIUS, OF NEW YORK, N. Y.

SHEET-POWDERING MACHINE.

Application filed November 16, 1925. Serial No. 69,283.

Embossed or engraved effects are produced by printing the desired copy, applying a suitable powder to the printed sheet, removing the excess powder from the printed portion of the sheet, and then baking the sheet so as to fix or set the powder. The powder employed is largely resinous in its nature or of shellac-like material, and as this is very finely divided, it is quite difficult to handle and has a tendency to lump and become sticky particularly in damp and warm weather so that it is extremely difficult to apply it where desired and even more difficult to remove it from places where it is not desired.

The main object of this invention is to provide a simple, compact and reliable mechanism for printing, applying powder to the printed sheets, removing excess powder, and baking the sheets to produce embossed effects.

A more specific object is to provide a machine of this character which can be operated at high speed and with a minimum of supervision.

In carrying out the invention I utilize the principles of some of my prior patents. I provide a horizontal moving wire mesh belt which constitutes a conveyer for the sheets which have been printed with suitable ink. The printed sheets may be deposited on the conveyer by hand or automatically from the printing press, but in the latter case a separate chute is provided to receive the printed sheet and discharge it on the conveyer leading to the powdering apparatus. Above the conveyer is located a hopper or feed device from which the embossing powder is discharged upon the sheets as they pass beneath it. The material in this hopper is vibrated so as to ensure the passage of a fine, thin stream of the powder uniformly and without sticking or clogging. After the powder has been deposited on the sheets, the sheets are subjected to treatment for removing the excess of powder. This may be accomplished in several ways for instance by means of air blasts.

Beneath the conveyer I provide a receptacle for receiving the powder which has not adhered permanently to the sheets. The powder which has not been used passes to the bottom of this receptacle and the powder is reconveyed to the hopper by means of a belt or chain having buckets, which conveyer dis-

charges into a distributor in the upper part of the hopper.

The powder ordinarily employed is extremely fine and if not controlled would be blown or sifted outside of the machine, would inconvenience the operators and waste powder. I therefore prefer to house the hopper and the conveyer and provide a suction device which will immediately remove the particles of powder which do not settle into the collecting receptacle at the bottom. The exhausted air created in process of cleaning sheets with suspended particles of powder may be carried to any suitable strainer or it may be returned through the outlets with the air which serves to remove the excess particles of powder from the printed sheets. As the sheets pass from the machine they may be discharged directly upon the conveyer leading to the usual heater or oven for baking or heating.

Fig. 1 is a side view of one form of machine embodying the improvements of my invention.

Fig. 2 is an end view and partial vertical section of the same.

Fig. 3 is a longitudinal vertical sectional view on the general plane of the line 3—3 of Fig. 2.

Fig. 4 is an enlarged detail view of the hopper.

Fig. 5 is a diagrammatic side view showing the connection between a printing press and the powderer.

The conveyer 5 is preferably formed of woven wire mesh driven in any suitable manner. The sheets to be powdered may be deposited either directly on this conveyer or from the discharge chute 6 leading from a printing press delivery or from the conveyer 6' which receives the printed sheet from the press. The powdered sheet is discharged by an inclined chute 7 to another conveyer 8 which leads to the oven 9.

Power may be supplied from motor 10 which drives a shaft 11. This shaft 11 drives another shaft 12 from which the roller 13 is driven and which in turn drives the conveyer 5.

The powder supply is initially placed in the receptacle 14 which is located below the conveyer and at one side of the machine or the powder may be placed in hopper 15 which extends entirely across the conveyer and has a

narrow slot at the bottom formed between two inclined plates 16 and 17. These plates should be quite stiff and perfectly straight along their meeting line. The plate 16 is 5 preferably vertically adjustable so as to vary the permissive opening at the bottom. The plate 17 may also be vertically adjustable but is secured at its upper end at 18 quite rigidly to the hopper so that it may act as a spring plate. Beneath the hopper is located a shaft 19 which has one or more shoulders which serve to engage the lower edge of the plate 17 and vibrate it as the shaft 19 is rotated. The discharge slot 20 need be only approximately 10 from 1/16th to 3/16ths of an inch wide. The vibration caused by the rotation of the shaft 19 vibrates the powder in the hopper so that the powder which is discharged into the hopper is sifted through the slot continuously 15 in a very fine or thin stream. The vibrator shaft 19 may be rotated by a belt 21 from the roller 13.

The conveyer 22 may be a suitable bucket type conveyer which dips into the receptacle 14 at the bottom and is driven from a shaft 23 and belt 24 from shaft 11. Above the hopper is located a distributor head 25 which is connected to the tube 26 which contains the conveyer 22. As the powder is thrown from 20 the conveyer 22 into the discharge head 25 it passes into the hopper 15. To insure uniform distribution I prefer to provide one or more inclined partitions such as 27 in the distributor head.

30 Beneath the sheet conveyer 5 I provide an inclined chute 28 which leads to the powder receptacle 14 so that the powder discharged from the hopper 15 and which does not remain on the sheets is returned to the receptacle 14.

In the form of machine herein shown I prefer to provide an air blast for removing the excess or surplus powder from the sheets on 35 the conveyer 5. This air blast may be produced by an air pump or blower 30 driven by any suitable source of power. Above the sheet conveyer 5 I provide a discharge pipe 31 with outlets in position so that the air may be discharged angularly in the direction of 40 the arrows as shown in Fig. 3 downwardly and against the direction of travel of the sheets. This discharge pipe 31 is connected by pipe 32 to the blower 30. As the sheets travel forwardly with the conveyer 5 the air currents from the discharge pipe 31 generally force the unattached or non-adhering powder along the sheet so that when the sheet passes under the pipe 31 all excess powder has 45 been removed. I preferably provide baffle plates such as 33 and 34 to deflect the powder which may otherwise tend to move outward through the inlet end of the machine.

Above the conveyer 5 and entirely surrounding the hopper 15 and the air pipe 31 50 I preferably provide a hood 35, the sides of

which are connected to the sides of the collecting chute 28. To this hood I attach a pipe 36 and connect it to a suitable evacuating or exhausting means such as the blower 30 so that any particles of powder floating in the air 55 above the conveyer 5 will be immediately withdrawn and prevented from settling on the sheets which are passing through the machine. It should be understood of course that the speed of the conveyer 5 may be regulated 60 as desired and that the speed of the blower may be regulated so as to provide more or less air pressure for removing the excess powder from the printed sheets. It will also be understood that the rate of vibration may be 65 adjusted by controlling the speed of rotation of the shaft 19. In fact with some classes of powder and when the air is very dry the apparatus will operate satisfactorily without requiring very much vibration. A valve 37 70 may be provided in the exhaust pipe if desired for partly controlling the suction. The supplemental suction connection may be effected at 38 if desired and controlled by a valve 39.

I prefer to provide the metal chute 6 intermediate the canvas conveyer 6' and the wire mesh conveyer 5 so as to prevent powder from the powderer from collecting on the conveyer 6' which leads from the printing press. This has been found to be very important since otherwise in a day's run a very considerable amount of powder may be carried back to the printing press and interfere with the satisfactory operation of the combined machine. The chute 6 may be readily cleaned.

The apparatus will be seen to be simple in construction and operation. By having the sheet conveyer 5 travel horizontally it is 105 possible to make the machine quite compact and yet capable of handling large as well as small sheets at a high rate of speed. The powdering device makes it possible to apply the ordinary commercial embossing powders uniformly and economically in all conditions of humidity. The means for removing the excess powder herein shown and described ensures not only a uniform distribution of the powder on the sheets but the complete removal of all excess powder and saves all of the powder which is not required for the embossing effect.

In the following claims it will be understood that I intend to cover the specified combination of elements or an equivalent thereof, and that the claims are not to be considered as limited in scope except as required by the prior art.

I claim:

1. A sheet powdering machine comprising a continuous belt conveyer, means for depositing powder on sheets on said conveyer, means for removing excess powder from said sheets, a collecting receptacle below said con- 130

- veyer and means for returning to said receptacle unused powder comprising a hood above said conveyer and a suction device connected to the upper part of said hood.
5. 2. A sheet powdering machine comprising a continuous belt conveyer, a powder receptacle below the conveyer, means including a hopper above the conveyer and means for vibrating material in the hopper for distributing the powder on sheets on the conveyer, means for raising powder from said receptacle to said hopper, air jet means for removing excess powder from the sheets, a hood, and suction means connected with the upper part of the hood for removing particles of powder from the air above said conveyer and for removing excess air to prevent powder from being blown out the entrance and exit for the sheets.
20. 3. A sheet powdering machine, comprising a foraminous belt conveyer, a suction hood extending over the upper run of the conveyer, a powder receptacle below said conveyer having downwardly converging walls, a powder discharging device in said hood and above said conveyer to distribute powder on sheets on said conveyer, means for blowing excess powder from the sheets on the conveyer, and means including a baffle between the runs of the conveyer and extending substantially from one run to the other for preventing blowing of the excess powder out of an end of the machine.
4. A sheet powdering machine, comprising a continuous conveyer, a powder receptacle beneath the conveyer and adapted to receive powder therefrom along the full length thereof, a suction hood above the upper run of said conveyer, means in said hood for distributing powder on sheets on the upper run of said conveyer, means in said hood to direct an air blast downwardly and rearwardly on sheets after passing the powder-distributing zone to remove excess powder from the cards, and means including a baffle between the runs of the conveyer and extending substantially from one run to the other to prevent the powder from being blown out through the inlet end of the machine.
5. A sheet powdering machine, comprising a continuous conveyer, a hood extending over the upper run of the conveyer, a powder receptacle below said conveyer, a powder discharging device in said hood and above said conveyer to distribute powder on sheets on said conveyer, means extending across the upper run of the conveyer for blowing excess powder from the sheets on the conveyer, suction means for withdrawing excess air from said hood and means including an inclined baffle between the runs of the conveyer and extending substantially from one to the other of said runs for preventing blowing of the excess powder out of an end of the machine.
6. A sheet powdering machine, comprising a continuous conveyer, a powder receptacle beneath the conveyer and adapted to receive powder therefrom along the full length thereof, a hood above the upper run of said conveyer, means in said hood for distributing powder on sheets on the upper run of said conveyer, means in said hood to direct an air blast downwardly and rearwardly on sheets after passing the powder-distributing zone to remove excess powder from the sheets, suction means connected with the hood at the top to withdraw excess air therefrom, and means including a downwardly and forwardly inclined baffle between the runs of the conveyer and beneath the powder-distributing means to prevent the powder from being blown out through the inlet end of the machine.
7. A sheet powdering machine, comprising a continuous conveyer, a powder receptacle beneath the conveyer and adapted to receive powder therefrom along the full length thereof, a suction hood above the upper run of said conveyer, means in said hood for distributing powder on sheets on the upper run of said conveyer, means in said hood and at the delivery side of the powder-distributing zone to direct an air blast downwardly and rearwardly to remove excess powder from the cards and means to prevent powder from being blown out through the ends of the machine including a baffle between the runs of said conveyer and extending substantially from one run to the other and a baffle extending downwardly from the lower run of the conveyer.
8. A sheet powdering machine comprising a wire mesh conveyer, means for depositing sheets onto one end of said conveyer, a hopper for dusting powder onto the sheets on said conveyer, means for removing excess powder from the sheets while on said conveyer, a suction hood enclosing the depositing and removing means and extending over the upper run of said conveyer, a collecting receptacle below said conveyer having its upper edges surrounding said conveyer and having its side walls converging downwardly and to one side of said conveyer, a pocket at the lower end of said receptacle, a vertically disposed chute extending upwardly from said pocket to a point above and to one side of said hopper, a distributing conduit extending from the upper end of said chute across said hopper, and a powder lifting conveyer in said chute and dipping into said powder pocket and discharging into said distributing conduit.

SAMUEL LIPSIUS.
